UNITED STATES PATENT OFFICE.

MAHLON E. LAYNE, OF MEMPHIS, TENNESSEE.

WELL APPARATUS.

1,299,741.

Specification of Letters Patent. Patented Apr. 8, 1919.

Application filed September 28, 1917. Serial No. 193,747.

To all whom it may concern:

Be it known that I, MAHLON E. LAYNE, a citizen of the United States, residing at Memphis, in the county of Shelby and State 5 of Tennessee, have invented certain new and useful Improvements in Well Apparatus, of which the following is a specification.

This invention relates to oil or water wells and has particular reference to the manner 10 in which the fluid is separated from the fluid bearing strata and filtered prior to its entry into the well pipe of the pump.

The particular object of the invention is to eliminate the more or less mechanical 15 straining of the fluid so common in present practice where metal screens of various kinds are used, and to substitute therefor a separation of the fluid which is more accurately described as a filtration thereof. In 20 present constructions the screening element is generally composed of a supporting frame, such, for example, as a perforated pipe or casing, around which is wound a helix of screening wire. My invention involves 25 in place of the above mechanical screen, the use of gravel and sand or some other suitable filtering material through which the fluid is directed before withdrawal, and which accomplishes the separation 30 thereof by a more or less natural filtering process, the velocity of the flow being low through the filtering material but the available area provided for separation being made much greater than in constructions 35 above described. My invention also contemplates the provision of a chamber for collecting the fluid after it is filtered and before it enters the withdrawing means or suction pipe of the pump. But to more 40 clearly understand my invention, reference should now be had to the drawings wherein I have illustrated it as applied to a water well.

Figure 1 is a vertical section illustrating 45 my invention taken at a point in a well where production is encountered; Figs. 2 and 3 are perspective views of a principal element of my invention; Fig. 4 is an illustration of a detail of the construction; Fig. 5 illustrates a modification of the invention; and Fig. 6 illustrates still another modification.

Referring to Fig. 1, I have indicated the suction pipe by the numeral 1. Around it 50 I place a series of ring-shaped members indicated as entireties by the letter A, the

specific construction of which is now to be described. Any desired number of these members A may be used at a given point in the well, the conditions of service and the 60 depth of the water bearing stratum in which they are placed being the determining factors. These members A may best be described as pans having a downwardly projecting flange at the periphery, the pan-like 65 depressions being indicated by the numeral 2 and the flange by 3. The pipe 1 passes through these pans at their deepest portion at which point they are provided with a downwardly projecting flange 4 for attachment to the pipe. Immediately above the 70 bottom of the pans are formed, in the pipe, perforations or holes 5 for entry of the water. Just above these holes, grates 6 are placed in the pans upon which the filtering 75 material rests. The filtering material 6^a is partially shown only in the upper pan of Fig. 1. The space or chamber 6^b thus formed in the bottom of the pan constitutes what I have termed a pre-collecting or separating chamber, which has for its outlet the openings 5 into the well pipe of the pump and which has over its entry portion the grate 6 and the filtering material 6^a. In 80 order to bind the members A together, lugs 7 on the upper face thereof and lugs 8 on the lower face are provided, the lugs on adjacent faces being adapted to be bolted together. The downwardly projecting lugs 8 have a portion 9 adapted to serve as retaining members for the grates, against which such portion abuts. The flanges 3 of the members A are made to extend far enough 85 down to protect the filtering material in the pan next below from the pressure of the surrounding formation. This provision prevents packing and hardening of the filtering material.

The modification disclosed in Fig. 5 shows 90 how the formation itself may be used somewhat as a filter. Outwardly and downwardly projecting domes 10 are arranged on the well pipe 1. The pans of the above described construction (though of slightly modified construction) are arranged beneath 95 the dome, as shown, the holes 5 in the pipe communicating with the chamber 6^b beneath the grate 6, also as previously described. The flange 12, forming the upper edge of the pan in this modification, abuts against 100 an annular projection 13 on the under face of the dome, and in this flange are cut-away

portions 14 through which the water flows. The great over-hang of the dome 10 holds the surrounding formation 15 away from the pipe and forms a pocket 16 thereabout, with the pan in about the center thereof, the formation assuming approximately the position indicated in part in Fig. 5. The water separates from the formation 15, fills the pocket 16, passes through the cut-away portions 14 and filters down through the filtering material on the grates into the chamber 6^b from which it enters the pipe and is drawn to the surface of the ground.

The great area of the separating surface 15 in the formation 15 from which the liquid flows makes it possible to maintain the velocity of the flow therethrough so slight that only the smaller particles will be entrained by the fluid to be carried up to the filtering material in the pan, which particles will in turn be taken from the water at this point by means of the filter. This double filtration of the fluid insures a supply unusually free from dirt. Furthermore, only a comparatively shallow pan and a minimum of filtering material are needed where the fluid is thus substantially separated from the formation before it reaches the filter proper.

In Fig. 6 I have illustrated a further modification of the invention which involves the provision of a second set of inlet openings 5^a located between the under faces of the pans and the upper surfaces of the domes and also the provision of movable means for directing the inflowing fluid through one or the other set or of closing off entirely all inflow. The means for accomplishing this result consists of a second perforated pipe 1^a located within the outer pipe 1 and adapted to be moved up and down therein. The perforations 5' in this inner pipe are shown in Fig. 6 in alignment with the perforations 5 of the outer pipe. By moving the pipe 1^a down until the perforations therein align with the openings 5^a in the outer pipe (shown in dotted lines at 5'') the flow through the holes 5 is cut off and flow through the holes 5^a effected. Upon further downward movement of the pipe 1^a, flow through both sets of openings may be cut off, in which case the openings in the pipe 1^a will assume some such position as is indicated by the dotted lines at 5'''. In this latter position when both sets of inlet openings are closed, water from the surface may be forced down through the pipe passing out at the bottom and up around the outside of the pipe and cleaning the apparatus of mud.

I claim:

1. In apparatus for filtering fluid in wells, the combination of a well pipe, a pan, a grate in the pan, and filtering material on the grate, the pan and its parts co-operating with the pipe in such manner as to filter the fluid before it enters the pipe.
2. In well apparatus, the combination of

a fluid collecting receptacle, a pan, and filtering material in the pan adapted to filter the fluid prior to its entry into the collecting receptacle.

3. In well apparatus, the combination of 70 a well pipe, two or more pans on the pipe arranged one above the other, and filtering material in the pans, the material in each pan being protected from pressure by the pan next above.

4. In well apparatus, the combination of 75 a perforated well pipe, two or more circular pans having central openings, arranged on the pipe one above the other, grates in the pans, and filtering material on the grates, the 80 pans and their contents being so arranged on the pipe with respect to the holes as to bring the said holes in each case between the grate and the bottom of its pan.

5. In well apparatus, the combination of 85 a well pipe, two or more pans on the pipe arranged one above the other, a grate in each pan, and lugs on the upper and on the under faces of the pans adapted to serve as coupling means therefor, the lugs on the under 90 surface of each pan serving also as retaining members for the grate in the pan below.

6. In well apparatus, the combination of 95 a well pipe having an inlet, a chamber about said inlet provided with a foraminous portion constituting the inlet to said chamber and extending substantially horizontally above the inlet in the collecting element.

7. In well apparatus, the combination of 100 a well pipe having an inlet, a chamber about said inlet provided with a filtering element constituting the inlet to said chamber, said filtering element extending horizontally above the inlet in the collecting element.

8. In well apparatus, an apertured casing, 105 and a plurality of superimposed filtering elements, each of said elements forming a protection for the one next below and so disposed that the flow from such elements into the apertured casing is in a downward direction.

9. In well apparatus, an apertured casing, and a plurality of superimposed filtering elements and so disposed that the flow from such elements into the apertured casing is in 115 a downward direction.

10. In well apparatus, the combination of a well pipe having a plurality of inlets therein, collecting chambers about certain of said inlets, and a pipe within the well pipe having 120 openings therein, said pipe with its openings being adapted to be moved to admit fluid either through inlets having collecting chambers or through inlets not having collecting chambers or to cut off admission of fluid.

11. In well apparatus, the combination of a well pipe having a plurality of inlets therein, collecting chambers about certain of said inlets, and a pipe within the well pipe having 125 openings therein, said pipe with its openings 130

being adapted to be moved to admit fluid either through inlets having collecting chambers or through inlets not having collecting chambers.

5 12. In well apparatus the combination of a substantially vertical delivery chamber and an upwardly inclined screening chamber ar-

ranged exteriorly of the delivery chamber and communicating therewith at its lower end. ¹⁰

In testimony whereof I have hereunto signed my name.

MAHLON E. LAYNE.
